Patented July 3, 1923.

Des. 62,604

UNITED STATES PATENT OFFICE.

JULIA WATSON DE SHIELDS, OF RIVERDALE-ON-HUDSON, NEW YORK.

DESIGN FOR A FOOT REST.

Application filed August 19, 1922. Serial No. 3,460. Term of patent 7 years.

To all whom it may concern:

Be it known that I, JULIA WATSON DE SHIELDS, a citizen of the United States, residing at Riverdale-on-Hudson, in the county of New York and State of New York, have invented a new, original, and ornamental Design for a Foot Rest, of which the following is a specification, reference being had to the accompanying drawing, forming part thereof.

The figure is a perspective view of a foot rest embodying my design.

I claim:

The ornamental design for a foot rest as shown.

JULIA WATSON DE SHIELDS.
